UNITED STATES PATENT OFFICE.

FRANCIS G. GALE, OF WATERVILLE, QUEBEC, CANADA.

BED-BOTTOM.

1,284,087.

Specification of Letters Patent.

Patented Nov. 5, 1918.

Application filed November 5, 1914, Serial No. 870,526. Renewed April 1, 1918. Serial No. 226,099.

To all whom it may concern:

Be it known that I, FRANCIS G. GALE, a subject of the King of Great Britain, residing at Waterville, Province of Quebec, 5 Dominion of Canada, have invented an Improvement in Bed-Bottoms, of which the following description, in connection with the accompanying drawing, is a specification, like characters on the drawing representing like parts.

This invention relates to bed bottoms of that type which are formed of a plurality of V-shaped links arranged in rows extending transversely across the bed bottom, each link having hooks at its free end which hook into the apices of the links of the next adjacent row.

In bed bottoms of this type it is customary to connect the ends of the bed bottom 20 to the end rails of the mattress frame by means of spiral springs, there being two spiral springs for each three links in the last complete row of links, and the connection between the two springs and the corresponding three links is secured by connecting links, one for each spring, said connecting links being arranged in pairs and the links of each pair being secured to three links in the last row of V links. In order to provide for this connection at each end of the bed bottom, it has heretofore been customary to make the bed bottom in two sections which are connected centrally of the bed bottom, the V links in each section being arranged with their apices toward the adjacent end of the mattress frame or bed bottom. Where this construction is employed the connecting links may be V-links similar in shape to the links forming the 30 body of the bed bottom. It involves considerable labor to make the bed bottom in two sections and then connect the sections together and connect each section to the mattress frame, and one object of my invention 40 is to provide a novel construction by which the bed bottom can all be made in one section and yet the proper connection between the bed bottom and the end rail of the mattress frame can be made at each end thereof. 45 I accomplish this by providing a special construction for the connection between the hooked ends of the links and the springs at the corresponding end of the mattress frame. In order to give an understanding 50 of my invention I have illustrated a selected

embodiment thereof which will now be described.

Figure 1 shows a perspective view of a mattress frame embodying my invention;

Fig. 2 is an enlarged fragmentary view 60 showing portions of the two ends of the bed bottom and the connection with the mattress frame;

Figs. 3 and 4 show the two special links employed.

The body of the bed bottom is made up of a plurality of V-shaped links 1, each having at each end thereof a hook 2. These links are arranged in rows extending transversely of the bed bottom and the hooks 2 of each link in one row are hooked into the apices 3 of two adjacent links in the next adjacent row. The bed bottom is sustained by a mattress frame, as usual, which is herein shown as comprising the side rails 4 and end rails 5 and 6, and the bed bottom is yieldingly connected to the end rails 5 and 6 through the medium of springs 7, as usual in bed bottoms of this type.

In my improved bed bottom the entire 80 body of the bed bottom is made up of these V-shaped links 1 which are arranged in rows, and all the links throughout the bed bottom have the same general position, that is, the apex of each link is directed toward 85 the end rail 6 of the mattress frame and the hooked ends 2 are directed toward the end rails 5. In the bed bottom shown there are two springs 7 for each three links in the last row of links 1 forming the body of the fabric 90 and the connection between each two springs and the corresponding three links 1 at the right-hand end of the bed bottom is accomplished in the usual way by means of pairs of links 8 and 18 herein shown as V-links 95 similar to the links 1, and each having hooks 9 at the ends of its arms. The hooked ends 9 of a pair of links 8 and 18 are hooked into the apices of three adjacent links, 1, as shown at the right in Fig. 2, and the apex 100 10 of each link 8 and 18 is connected to a spring 7. Where the entire body of the bed bottom is made up of links 1 which point in the same direction the last row of links 1 at the left-hand side of the bed bottom, which 105 row is designated generally by reference letter *a*, will all have their hooked ends 2 directed toward the end rail 5, and in order to provide a construction whereby three of these links may be connected to two springs 110

7, I propose to use the special form of connecting links shown in Figs. 3 and 4 and designated 11 and 12, respectively. The connecting link 11 is V-shaped and is provided 5 with an eye 13 at the end of each arm thereof. The link 12 is also V-shaped and is provided with an eye 14 at the end of one arm and a hook 15 at the end of the other arm. In using these links 11 and 12 to connect the 10 last row *a* of links 1 to the spring 7 so as to provide two springs for each three links, I employ the links 11 and 12 in pairs, the apex of each link being connected to a spring 7. A link 11 is placed directly opposite every 15 third link 1 in the row *a* and the hooked portions 2 of each third link 1 are hooked into the eyes 13 of the corresponding link 11. The link 12 is secured to the adjacent spring 7 and the hook 15 thereof is hooked into one 20 of the eyes 13 of the link 11 and the eye 14 of said link 12 has engagement with the hook of one of the arms of the link 1 adjacent said third link. Said link 1 which is adjacent the third link is hooked into the eye 13 of the 25 link 11 and the eye 14 of the link 12. The link 1 on the other side of said third link is hooked into the eye 13 of the link 11 of one pair 11 and 12, and the eye 14 of the link 12 of the next adjacent pair. By this construction 30 the required connection from the hooked ends of the links 1 in the row *a* can be made to the spring 7 connected with the end rail 5, so that two springs 7 will be employed for each three links in the row *a*, as at the other 35 end of the bed bottom. It is thus possible to make the body of the bed bottom in one section instead of two sections connected together at the center, and by this means the manufacturing operation is greatly facilitated. At the same time, however, the same 40 number of springs 7 is used at each end of the bed bottom.

The links 8, 18 are especially made so as to permit the springs 7 connecting said links 45 with the end rails 6 to be evenly spaced. Fig. 2 plainly shows this. These links are each made with one leg slightly longer than the other, the links of each pair being arranged so that the longer legs of each pair 50 are adjacent each other. For instance, in the link 8 the leg 20 is shorter than the other leg 21, while in the link 18 the leg 22 is longer than the leg 23. These links are arranged with the longer legs 22, 21 adjacent each 55 other, thus throwing the apices 10 of the

pairs of links farther apart than would be the case if the two legs of the link were of the same length. By this means the springs 7 are evenly spaced from each other and they stand in parallel lines. 60

Similarly, the links 11 and 12 are made with one leg longer than the other. In the link 12 the leg 25 is longer than the leg 24, and in the link 11, the leg 26 is longer than the leg 27. By this means the apices 30 of 65 each pair of links 11 and 12 are situated slightly farther apart than the distance from one link 1 to the next link 1, and by properly proportioning the legs of the links the springs 7 may be equally spaced apart. 70

The edge of the bed bottom is made up of specially-constructed links 31 each having a long and a short leg, as best seen in Fig. 2.

I claim:

The combination with a mattress frame 75 having side and end rails, of a bed bottom, the entire body of which is composed of V-shaped links arranged in rows extending transversely of the bed bottom, each link having hooks at the ends of its arms and the 80 hooks of the links of each row being hooked into the apices of the links in the next adjacent row, all of the links of the bed bottom having their apices directed toward the same end of the mattress frame, means for 85 connecting the apices of the last row of links at said end of the mattress frame to the corresponding end rail thereof, and a pair of V-shaped connecting links for connecting each adjacent set of three V-links in the last 90 row at the other end of the bed bottom to the corresponding end rail, each pair of V-shaped connecting links comprising one link having eyes at both ends of its legs and the other link of each pair having an eye at 95 the end of one leg and a hook at the end of the other which hooks into an eye of the other link of the pair whereby each pair of connecting links presents three eyes into which the hooked ends of said last row of 100 V-links are hooked, and a spring connecting the apex of each connecting link to the end rail.

In testimony whereof, I have signed my name to this specification in the presence of 105 two subscribing witnesses.

FRANCIS G. GALE.
